US00D887477S

(12) **United States Design Patent** (10) **Patent No.:** **US D887,477 S**
(45) **Date of Patent:** **** Jun. 16, 2020**

(54) **SURVEILLANCE CAMERA ENCLOSURE**

(71) Applicant: **Parabit Systems, Inc.**, Roosevelt, NY (US)

(72) Inventors: **Luis Emilio Vega**, Woodland Park, NJ (US); **Mohammad Hasani**, Brooklyn, NY (US)

(73) Assignee: **Parabit Systems, Inc.**, Roosevelt, NY (US)

(**) Term: **15 Years**

(21) Appl. No.: **29/633,145**

(22) Filed: **Jan. 12, 2018**

(51) LOC (12) Cl. **16-01**

(52) U.S. Cl.

USPC **D16/214**; D16/203

(58) **Field of Classification Search**

(57) **CLAIM**

The ornamental design for a surveillance camera enclosure, as shown and described.

DESCRIPTION

FIG. 1 is a top, front and right side perspective view of a first embodiment of a surveillance camera enclosure showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a bottom plan view thereof;

FIG. 7 is a top plan view thereof;

FIG. 8 is a top, front and right side perspective view of a second embodiment of a surveillance camera enclosure showing our new design;

FIG. 9 is a front elevational view of FIG. 8;

FIG. 10 is a rear elevational view of FIG. 8;

FIG. 11 is a right side elevational view of FIG. 8;

FIG. 12 is a left side elevational view of FIG. 8;

FIG. 13 is a bottom plan view of FIG. 8; and,

FIG. 14 is a top plan view of FIG. 8.

The broken lines depict portions of the surveillance camera enclosure in which the design is embodied that form no part of the claimed design.
